UNITED STATES PATENT OFFICE.

ALBERT E. DONLEY, OF PROVIDENCE, RHODE ISLAND.

DESIGN FOR A STOPLIGHT.

Application filed July 15, 1925. Serial No. 14,109. Term of patent 7 years.

To all whom it may concern:

Be it known that I, ALBERT E. DONLEY, a citizen of the United States, residing at Providence, in the county of Providence and State of Rhode Island, have invented a new, original, and ornamental Design for a Stoplight, of which the following is a specification, reference being had to the accompanying drawings, forming part thereof.

Fig. 1 is a front view of the invention.

Fig. 2 is an edge elevation of the invention.

I claim:

The ornamental design for a stoplight as shown.

In testimony whereof I have signed my name to this specification.

ALBERT E. DONLEY.
